MICROWAVE PHASE SHIFTER

John F. Zaleski, Valhalla, N. Y., assignor to General Precision Laboratory Incorporated, a corporation of New York

Application December 29, 1951, Serial No. 264,094

6 Claims. (Cl. 333—9)

1

This invention pertains to microwave phase shifters of the type used for changing the relative phase of microwave energy in two transmission lines.

In any microwave transmission line the transmission of energy is accomplished by means of an electromagnetic field guided by the line conductors, boundaries or walls and, since the energy follows the laws of wave motion, the interrelation of the electric and magnetic energy forms changes from point to point along the transmission line, this interrelation being termed the phase. Any transmission line device that effectively adds or subtracts length from the transmission line thereby changes the phase of the microwave energy at any selected subsequent location, and this method is used to change or shift the phase of microwave energy.

In the instant invention the effective guide length is changed in an unique manner, and at the same time the applied microwave energy is divided into two exactly equal parts. That is, in this invention a phase shifter is combined with a power divider to form an instrument especially suitable for particular purposes. For example, the device of the instant invention is particularly useful for periodically changing the relative phase of microwave energy fed to two antennas, so that the two antennas will alternately emit energy in phase and 180° out of phase, their intensities of emission being the same in both cases. This result is advantageously accomplished by the invention because of its high efficiency in the switched positions and because of the simplicity of the arrangement to produce a phase shift of precisely 180°.

Briefly the invention provides a rectangular hollow guide to serve as a microwave energy input and a second rectangular hollow guide attached to the first guide to serve as a pair of outputs. A two-position switching arrangement is provided at the point of attachment of the two guides.

One object of this invention then is to provide a microwave hollow guide phase shifter that shifts the phase relation of two hollow microwave guide connections from a first value to a second value.

Another object is to provide a combined phase shifter and power divider that divides input microwave power into two exactly equal output parts having a phase relation switchable by exactly 180°, the losses in the switched positions being negligible.

Still another object is to provide a microwave phase switch that switches the relative phase of

2

two microwave energies from one value to another value without affecting the relative magnitude of the energies.

Further understanding of the invention may be secured from the detailed description and the associated drawings in which:

Figure 1 is a general view of a phase shifter embodying the invention.

Figs. 2 and 3 are cross-sectional views of Fig. 1 taken on the lines 2—2 and 3—3 respectively.

Referring now to Fig. 1, a rectangular hollow microwave guide 11 short-circuited by a conductive plate 12 at one end is arranged for excitation at the other or input end by microwave energy generated at 13. Another rectangular hollow microwave guide 14 of similar cross-sectional dimensions is joined at right angles to the guide 11, the two guides being interconnected by a short square box 16 serving to provide space for a rotatable operating shaft 17 and its associated choke bearing 18. This construction brings the plane of the lower broad side of guide 11 parallel to the plane of the upper broad side of guide 14 but separated therefrom by the length of the box 16. The guide 14 is loaded at its two output ends or terminals 19 and 21 by utilizing apparatus having impedance equal to the guide characteristic impedance to avoid reflections, in accordance with standard practice.

The junction of the guides 11 and 14 comprises a passage including an aperture in the lower broad side of the guide 11, the interior space of the box 16, and an aperture in the upper broad side of the guide 14, so that the passage provides access from the field space within the hollow guide 11 to the field space within the hollow guide 14.

The passage is of square cross-sectional shape throughout its length, the length of one side being equal to the larger cross-sectional dimension A, Fig. 2, of the hollow guide. This is the maximum value that either side of the area can have although either or both sides can be smaller as will be explained later.

The distance from the end plate 12, Fig. 1, to the center line 22, Fig. 2, of the junction area is made approximately $\lambda_g/4$, λ_g being the wavelength in the guide of the energy supplied to the guide 11 by the microwave generator 13, to produce the maximum transfer of energy from guide 11 to guide 14. This distance, however, departs from the exact value of $\lambda_g/4$ by an amount sufficient to match out the junction discontinuity.

The shaft 17, Fig. 2, is parallel to the axis of guide 11 and bisects the area of the aperture. The shaft is journaled in two conventional choke

bearings 18 and 23, although it may alternatively be journalled in the single bearing 18 and terminated near but not touching the side 24 of the square aperture.

A conductive rod 26 is secured at one end to the shaft 17, extending normal thereto in a plane midway of the transverse dimension of the wave guide 14. This rod has a length such as to just clear the sides 28 and 29 of the aperture and the lower broad side 31 of the wave guide 14 when the rod is rotated by the shaft 17.

The shaft 17 acts to divide the rectangular aperture defined by the sides 24, 28, 29 and 32, Fig. 2, into two equal windows, each of which will support microwave transmission in only the dominant mode. One window is defined by the shaft 17 and the aperture sides 24, 28 and 32, and the other window is defined by the shaft 17 and the aperture sides 24, 29 and 32.

The rod 26 when positioned to span either window, acts to interdict that window to the transmission of microwave energy, because the rod divides the window into two equal areas, neither of which is large enough to support the applied microwave energy in any mode. A rod of this character thus serves substantially the same purpose as a solid metal shield in preventing the passage of microwave energy through the window.

When either of the windows is left open, that is, not spanned by the rod 26, that window constitutes a longitudinal slot in a broad side of the guide 11 which is displaced from its longitudinal center line, the window length being equal to the dimension A and the width being less than one-half A by the amount of the radius of the shaft 17. However, the width may be made as small as desired although the coupling coefficient will decrease with the width. Such a slot in a guide has the property of radiating microwave energy out of the guide and the discontinuity which it presents to the source can be matched out almost completely by a suitable matching device. Such a matching device is constituted by the end plate 12, which as heretofore stated is placed at a distance from the rectangular orifice mid-point departing from $\lambda_g/4$ by an amount sufficient to match out the impedance discontinuity.

An unspanned window can also be considered as constituting a series opening as respects the guide 14. Such a series opening can couple energy to the guide if the length of the opening, which lies transversely across the guide, is greater than the cutoff value of the dimension A for the applied frequency, this cutoff dimension being approximately one-half of the wavelength in free air of the applied energy. Any impedance discontinuity presented by this series opening is matched by the previously mentioned departure of the spacing of the end plate 12 from a distance of $\lambda_g/4$.

When such a series opening in the broad face of a wave guide is employed to couple microwave energy into the guide, the energy is transmitted from the opening in both directions in the guide in equal amounts and in opposite phases. For example, referring to Fig. 3, if the distances B and C from the window center plane 33 to the ends 19 and 21 of guide 14 be made equal, the energy leaving the end 19 will have a phase 70 exactly opposite to the phase of that leaving the end 21.

If the rod 26 be moved to the position indicated by the dotted lines 34, the rod interdicts the window bounded by shaft 18 and sides 24, 28

and 32, and leaves the window open bounded by the shaft 17 and sides 24, 29 and 32 and having a center plane 36. All microwave energy applied from guide 11 is then coupled through the latter window to guide 14 and none is coupled through the other window. If the dimensions of the device are made such that the distance D between the center planes 33 and 36 is exactly $\lambda_g/4$, then the distance E from the center plane 36 to the terminal 19 is longer than the distance B by $\lambda_g/4$, so that the phase of microwave energy arriving at 19 is retarded by the amount $\lambda_g/4$. Also, the distance F from plane 36 to terminal 21 is less than the distance C by $\lambda_g/4$, so that the phase of microwave energy arriving at 21 is advanced by $\lambda_g/4$. The total advance that has been effected in the phase of the one output terminal 21 relative to the other output terminal 19 is thus $\lambda_g/2$. The instantaneous phases of these terminals are thus opposed when the rod 26 is in the full-line position, and alike when the rod 26 is in the dotted line position 34.

The device of the invention is also reversible. If two microwave energies of appropriate frequency, exactly equal in amount and exactly opposite in phase, be applied at the terminal 19 and 21, the rod 26 being in the full-line position, the two energies add to form output energy at the end of guide 11 that is indicated in Fig. 1 as connected to a generator. Also, if the rod is in the dotted position 34 and equal amounts of equally phased energy be applied to the terminals 19 and 21, they will add in opposite phase at the center plane 36 and pass out the guide 11, 25 as before.

When microwave energy is transmitted through this device, the voltage standing wave ratio is found to be very low with the rod 24 in either of its two interdicting positions, but during movement of the rod from one position to the other an appreciable mismatch will occur. However, less mismatch will occur as indicated by reflection into the guide 11, when that guide is used as the input arm, if the motion of the arm 24 is 45 downward as indicated by the arc 37, rather than in the opposite direction.

If the dimension D is not equal precisely to $\lambda_g/4$ the relative phase change at the terminals 19 and 21 will not be exactly $\lambda_g/2$, or 180° , but will be proportional to the distance D, or the phase change in degrees will equal $720 D$ divided by λ_g . In order to make the phase change an exact reversal or 180° , D must equal $\lambda_g/4$, being measured always between the center planes 33 and 36. The distance between these planes can be reduced by reducing the distance between the sides 28 and 29 of the box 16, Fig. 2, and can be increased by increasing the diameter of the shaft 17. By manipulation of either or both of these variables, which can be done within wide limits without materially affecting the efficiency of the device, the dimension D can be made exactly equal to $\lambda_g/4$ or to any other value desired that is not too far removed therefrom.

What is claimed is:

1. A microwave phase shifter comprising, first and second rectangular wave guide sections positioned in overlapped relation with their broad faces in parallel planes and their axes in planes normal to each other to form a T junction, a communicating aperture in adjacent broad faces of said wave guide sections forming an energy transmission path therebetween, said aperture having a length in a direction transverse to said second wave guide section such that the full

length thereof will transmit microwave energy while substantially less than the full length thereof will prevent the transmission of such energy in any mode, a reflective termination for one end of said first wave guide section, and conductive means selectively positioned to intercept one half or the other half of the width of said aperture by dividing said one-half or the other half width into two portions, the lengths of each of which are insufficient to support the transmission of microwave energy.

2. A microwave phase shifter comprising, first and second rectangular wave guide sections positioned in overlapped relation with their broad faces in parallel planes and their axes in planes normal to each other to form a T junction, a communicating aperture in adjacent broad faces of said wave guide sections forming an energy transmission path therebetween, said aperture having a length in a direction transverse to said second wave guide section such that the full length thereof will transmit microwave energy while substantially less than the full length thereof will prevent the transmission of such energy in any mode, one end of said first wave guide section being reflectively terminated, a rotatable shaft parallel to said first wave guide and dividing said aperture into two equal windows, and a rod secured to said shaft and extending normal thereto to partly bisect one or the other of said windows in accordance with the rotatable positioning of said shaft.

3. A microwave phase shifter comprising, first and second rectangular wave guide sections positioned in overlapped relation with their broad faces in parallel planes and their axes in planes normal to each other to form a T junction, communicating aperture means in adjacent broad faces of said wave guide sections forming an energy transmission path therebetween, said aperture means having a length in a direction transverse to said second wave guide section such that the full length thereof will transmit microwave energy while substantially less than the full length thereof will prevent the transmission of

such energy in any mode, a metal plate terminating one end of said first wave guide section positioned parallel to the center plane of the width of said aperture means and at a distance therefrom approximately one quarter of an odd integer of the wavelength of the energy in guide, a rotatable shaft parallel to said first wave guide section and dividing said aperture means into two equal windows, and a conductive rod secured to said shaft and extending normal thereto to partly bisect one or the other of said windows in accordance with the rotatable positioning of said shaft.

4. A microwave phase shifter in accordance with claim 3 in which the maximum dimensions of said aperture means are equal to the greater internal cross-sectional dimensions of said guide sections and the minimum length of said aperture means in the direction transverse to said second wave guide section is greater than one-half wavelength in free space of applied microwave energy.

5. A microwave phase shifter in accordance with claim 3 in which the adjacent broad faces of said wave guide sections are spaced from each other and said aperture means includes a short rectangular guide section supporting said shaft.

6. A microwave phase shifter in accordance with claim 3 in which the parallel center lines along the length of said windows are separated by a distance of one-quarter wavelength in guide of the applied microwave energy.
